United States Patent Office.

THOMAS J. CHUBB, OF WILLIAMSBURG, NEW YORK.

Letters Patent No. 97,761, dated December 14, 1869; antedated June 14, 1869.

IMPROVEMENT IN REDUCING ORES.

The Schedule referred to in these Letters Patent and making part of the same.

To all to whom it may concern:

Be it known that I, THOMAS J. CHUBB, of Williamsburg, Kings county, in the State of New York, have discovered and invented new Improvements in the Process of Reducing Ores, melting and refining metals, and producing an improved quality of combustible gas; and I do hereby declare that the following is a full and exact description thereof.

The nature of my invention and improvement consists in producing a revibrating, agitated motion to a current or currents of flame in a combustion-chamber, or to the gases, or to the air in the passages leading to a combustion heating, melting, or refining-chamber, producing a perfect combustion and an intense heat, and causing the same heated gases or flame to repeatedly pass, revibrate, and repass the article or substance intended to be heated, and continuously impinging fresh atoms of the heated gases against the substance to be acted upon by the heat, avoiding an intense, cutting blast, and producing a great economy of fuel.

Also, in producing a revibrating, agitated motion to the ore, steam, or gases in contact with, or around, in and amongst heated coal or other fuel, carbonaceous or gas-producing substances in the furnace, or in a gas-producer, whereby the current of air, steam, or gases admitted into the furnace, is caused to enter into the cavities between, amongst, and through the fuel, and then revibrate or repeatedly passing and repassing in and out and through and amongst and into each and every cavity, and is held in near contact with the burning or heated carbonaceous matter, until each and every atom of oxygen contained in said current of air, steam, or gases, is combined with a portion of the carbon, and passes off as carbonic oxide, and the steam or moisture is fully decomposed, and the hydrogen, or a portion thereof, combined also with a portion of the carbon, and finally passes off as carburetted hydrogen, producing a richer, a more inflammable, and a higher heat-producing gas, with a whiter flame, than is usually produced by a steady current of air, steam, or gas, and avoiding the production and mixture of so large a proportion of useless gases as is usually produced by other means.

To enable others skilled in the art to use my invention and improvement, I will proceed hereby to describe the

Mode of Operation.

To produce the reciprocating, intermittent, or revibrating motion to a current of air, steam, gas, or gases, I employ a machine constructed similar to a pump without any valves, or similar to a bellows without a valve-opening, or any of the well-known mechanical devices for producing a backward and forward motion to a column of air or gas in a pipe or

flue, and producing, intermittently, a slight pressure, and then a partial vacuum in said pipe or flue.

To employ this agitating motion of a column of air entering into a heating or melting-furnace, the combustible gas should be conducted into the heating or melting-chamber in one flue or passage, and the vibrating current of air, either in a heated or cold condition, should be conducted into said chamber or place of combustion by another flue or pipe. The effect produced is, that the whole of the air or gas or gases entering in this chamber is constantly in a highly-agitated condition, changing and interchanging positions, mingling the atoms of gas and air with a rapidity only equalled by an intense blast similar to a blow-pipe. The supply of fresh air in said pipe or flue may be drawn, forced, or admitted, by a separate passage, into said main pipe.

This agitating-motion may be employed in most all places where great heat is required, and a perfect combustion of the gas or fuel is the result.

To produce a superior quality of combustible gas, I employ a gas-producing furnace or apparatus similar to those shown in my previous patents, or any other construction of apparatus.

I close all the openings below the fuel, and admit the air or steam, or both, for supporting combustion, by and through a large pipe, from six to ten times as large as would be required to supply the required amount of steam, air, &c., to support combustion by a steady blast. This pipe communicates with the gas-producers, or with each of them, by a large opening, with an adjustable valve to each opening; and in communication with this large main pipe, I arrange and attach a large pump without any valves, or some other equivalent mechanical device, so that when the piston of the pump is operated backward and forward, so also are the air, steam, &c., in the main pipe, and in and throughout all parts of the gas produced, and through the coal, coke, or other carbonaceous gas-producing substances therein, by which means I repeatedly force the air, steam, &c., in and out of every cavity in the fuel, interchanging the air or gases in said cavities with such great rapidity that a sufficiently high degree of heat is produced to effectually and perfectly decompose the air, steam, and carbonaceous matter with a very small amount of fresh air or steam being admitted, (comparatively with a steady blast.) With some kinds of coal, after the proper heat has been attained, the air may be omitted entirely, and the oxygen required to form carbonic-oxide gas with the coke, (or carbon of the fuel,) may be derived entirely from the decomposed water or steam.

By extracting the oxygen from steam, in place of atmospheric air, I prevent the mixing and impoverishing of the highly combustible quality of the gas with nitrogen from the air.

I thus produce a gas that is capable of supporting

a higher degree of heat when burned in hot or cold atmospheric air, than is usual in the old way.

This improved quality of gas may be employed for all purposes where heat and light are required, with great economy.

What I claim, is—

1. Effecting the heating, reducing, melting, or refining of ore, metals, metallic or earthy substances by aid of an agitated intermittent reciprocating or revibrating motion to a current or blast of air or gas entering the combustion-chamber of a furnace, for the purpose of producing a perfect combustion of the air and gases, and for the purpose of facilitating the action of the heated gases or flame to heat the metal (or other substance to be acted upon by the heated gases) without a cutting blast.

2. The employment of an agitating, revibrating

motion to air, steam, gas, or gases passing through or amongst particles of coal or other carbonaceous matter in a gas-producing furnace or apparatus, for the purpose of aiding the production or improving the quality of combustible gas.

3. Effecting the heating, reducing, melting, or refining of ores, metals, metallic or earthy substances by aid of gas, produced substantially as set forth.

4. Producing combustible gas by aid of an agitated intermittent reciprocating or revibrating motion to the air, steam, gas, or gases in immediate contact with the coal or other carbonaceous substances in a gas-producing furnace or apparatus.

THOS. J. CHUBB.
